UNITED STATES PATENT OFFICE.

ILIAS LADISHENSKY, OF KIEFF, RUSSIA.

FIRE AND WATER TUBE BOILER.

1,195,367.

Specification of Letters Patent. Patented Aug. 22, 1916.

Application filed April 7, 1916. Serial No. 89,670.

To all whom it may concern:

Be it known that I, ILIAS LADISHENSKY, engineer, residing at 112 Mariinsko-Blagoveshchenska street, Kieff, South Russia, have 5 invented certain new and useful Improvements in Fire and Water Tube Boilers, of which the following is a specification.

This invention relates to a combined fire-tube and water-tube boiler, the main objects 10 of the invention being to provide an improved boiler which is compact in construction, light in weight, may be readily cleaned, and has a very efficient system of circulation of the water.

15 The boiler is also adapted for use either as a marine, locomotive, or stationary boiler.

Referring to the accompanying drawings which illustrate the preferred form of the improved boiler: Figure 1 is a sectional side elevation, Fig. 2 is a horizontal section, 20 Fig. 3 is a rear view with the rear wall removed, Fig. 4 is a front view, Fig. 5 is a detail sectional view of a modification of one part of the boiler, and Fig. 6 is a detail sectional view of a modification of another part of the boiler.

A main cylindrical shell *a* is provided with longitudinal fire tubes *f* passing therethrough, and through the rear plate of said 30 shell is passed the upper ends of water-tubes *b* entering near the top of the boiler adjacent the water level. The lower ends of said water-tubes *b* enter a mud collector *c*.

35 Under the cylindrical shell *a* is arranged the furnace *h*, having the fire grate *i* extending from the fire bridge *n* to the front of the furnace adjacent the fire door *O*. Below the fire grate is the ash pit *S*.

40 Water tubes *d* extend underneath the shell *a* from the front of the boiler to the rear and preferably run along the sides of the furnace *h* arranged in two groups each lying in a plane inclined inwardly from the vertical as indicated in Figs. 3 and 4. These tubes may be covered with fire bricks if desired.

At the front of the boiler the tubes *d* are 50 led into chambers *e* which are provided with removable doors or covers *m*. At the rear end of the boiler the tubes *d* are led into similar chambers *e* located above, and at the ends of, the mud collector or drum *c*. The back chambers *e* are carried by the mud

collector *c* and are in communication therewith through suitable openings or pipes *g*. The front chambers *e* are in communication with the lower part of the front end of the shell *a* by suitable means such as short tubes *r*. 55

The various parts of the boiler are surrounded by an iron casing *h*, the space between this casing and the rear water tubes *b* being filled with brickwork or other fire proof material as shown. 60

In operation the gases of combustion pass from the furnace *h* over the fire bridge *n*, then upwardly adjacent the rear water tubes *b*, through the fire tubes of the shell *a* into the chimney or uptake *t*. 65

The water is fed either into the front chambers *e* or into the mud collector *c* and assuming it to be fed into the latter the circulation is as follows: Rising in the vertical water tubes *b* it passes into the rear 70 of the shell *a* near the surface of the water therein where it mingles with the heated water rising in the shell *a* itself. At the front end of the shell *a* where the water is not so highly heated it passes out at the lower 75 part into the front chambers *e* and thence into the front end of the tubes *d*, along the same to the rear chambers *e* and tubes *g* (Fig. 3), and back to the rear end of the shell *a*. 80

Instead of the tubes *b* being bent at the top they may lead into an additional chamber *p* in communication with the shell *a* as shown in Fig. 5. The shape of the shell *a* may also be modified as for example into 85 the saddle shape shown in Fig. 6, the furnace space *h* in such case being located in the semi-tubular lower part.

What I claim is:

In a steam boiler the combination of a 90 main shell, fire tubes passing therethrough, a flue or uptake at the front end of said shell, a furnace beneath the same and from which the gases of combustion are adapted to pass to the rear ends of said fire tubes, 95 substantially horizontal water pipes located below the shell and extending through said furnace from the front to the rear of the boiler, a front chamber arranged outside the boiler at the front end thereof said chamber being in communication with the lower 100 part of the shell and with the said water pipes, a rear chamber arranged inside the 105

boiler at the rear end thereof and in communication with the said water pipes, a mud collector arranged below said rear chamber and in communication therewith, and 5 pipes for connecting said rear chamber and said mud collector to the rear of the shell adjacent the water level therein.

In testimony whereof I affix my signature in presence of two witnesses.

ILIAS LADISHENSKY.

Witnesses:

H. A. LOVIAGUINE,
AUG. MUGHIS.
